CLAIM

The ornamental design for an egg tray, as shown and described.

DESCRIPTION

FIG. 1 is a front view of an egg tray showing our new design;

FIG. 2 is a rear view of the egg tray;

FIG. 3 is a left side view of the egg tray, a right side view being a mirror image thereof;

FIG. 4 is a top view of the egg tray, a bottom view being a mirror image thereof; and,

FIG. 5 is a top front side perspective view of the egg tray.

1 Claim, 4 Drawing Sheets
